UNITED STATES PATENT OFFICE.

WILLIAM AITKEN, OF LIVERPOOL, ENGLAND.

TELEPHONE SWITCHING SYSTEM.

1,110,027.

Specification of Letters Patent.

Patented Sept. 8, 1914.

Application filed October 24, 1910. Serial No. 588,645.

To all whom it may concern:

Be it known that I, WILLIAM AITKEN, a subject of the King of England, and a resident of Liverpool, England, have invented 5 a new and useful Improvement in Telephone Switching Systems, of which the following is a specification.

My invention pertains to telephone switching systems, and relates especially to 10 a novel and improved method of switching particularly applicable in branch exchange systems.

My invention has for its object to provide switching mechanisms and circuits whereby 15 automatic disconnecting facilities are afforded on connections between the central exchange and extensions of a branch exchange.

At the present time branch exchange 20 switchboards are so arranged that clearing or supervisory signals are displayed at the branch exchange switchboard on all connections made through the switchboard. This clearing signal is given when the subscriber 25 replaces his receiver on the hook at the termination of a conversation, and is the same whether the connection be of local or extension lines to each other, or of an extension line to an exchange trunk line. The 30 clearing signal, in case of a connection between an extension line and exchange trunk line, is given to the central exchange operator when the private branch exchange operator disconnects the connecting cords or circuits from the exchange trunk line. For 35 example, if a connection has been made at a private branch exchange between a central exchange and an extension line terminating in the private branch exchange, and the receiver at the extension station is replaced upon the hook at the termination of the conversation, the clearing signal will show only at the branch exchange, the branch exchange connecting or transfer circuit being 40 so arranged as to prevent the display of the clearing signal at the central exchange.

Should there be no regular operator at the branch exchange, or should the operator be negligent in removing the connecting circuit from the exchange trunk line, the central exchange operator under these conditions is usually instructed to disconnect from the trunk line upon receiving the supervisory signal from the central exchange subscriber. This leaves the trunk

line, which the branch exchange subscriber was previously using and with which he is still connected, apparently available at the central exchange for other connections. The exchange operator may, therefore, use this 60 trunk in attempting to complete a connection to this private branch exchange and will probably fail to get the branch exchange operator, but will obtain connection through the branch exchange with the extension line previously connected, thereby causing confusion and a delay in securing the connection desired. Again, if an extension line subscriber, after the termination of a central exchange connection, 65 desires a connection to an extension line terminating on the branch exchange board, and if the branch exchange attendant is attending to other duties or has been negligent in removing the connecting circuit or clearing 70 the previous connection, the subscriber will, when he attempts to signal the branch exchange operator and give his order for the extension line connection desired, experience considerable delay in securing the connection. 75

In my invention I employ novel and improved means whereby, on a connection through the branch exchange between any extension line and the central exchange, 80 there is obtained, when the extension subscriber replaces his receiver on the hook at the termination of a conversation, an automatic disconnect at the branch exchange, which restores all apparatus and lines employed in the connection to normal and at the same time gives the central exchange a clearing signal, thereby insuring a positive 85 operation between the branch exchange and the central exchange and preventing delays 90 occurring at the central exchange, due to slow operating on the part of the attendant at the branch exchange, and thus increasing the efficiency of operating. 95

In the drawings which accompany and 100 form a part of this specification, I have illustrated, and will subsequently describe, two forms or embodiments of my invention, one applicable to use with common battery systems and one arranged to use with mag- 105 neto systems.

Figure 1 shows a sectional elevation of my improved switching mechanism taken on the line A—A of Fig. 2; Fig. 2 illustrates a section of the same taken on the line B—B of 110

Fig. 1; Fig. 3 shows a detail of the ratchet mechanism taken on the line C—C of Fig. 1; Fig. 4 shows in diagram complete apparatus and circuit arrangements of my invention as applied to a branch exchange of the common battery type; Fig. 5 shows in diagram complete apparatus and circuit arrangements of my invention as applied to magneto type branch exchange. Fig. 6 represents in diagram an alternative method of supplying current for the operation of my device when the device is used with common battery systems.

Referring especially to Figs. 1, 2 and 3, in which like numerals indicate corresponding parts throughout, I will first describe the switching mechanism in detail that its action in the circuits may be more fully understood in subsequent disclosures. Fig. 1 shows what I will call a multi-contact electromagnetic switch, by which, in connection with certain circuit arrangements, I am enabled to maintain connections electromagnetically during conversation, and to attain automatic disconnection of such connections on the cessation of conversation. In the figure an electromagnetic coil 12 is carried on a core 12', and is provided with a magnetic cup 15, which serves to bring the poles in such relation that the magnetic circuit may be closed by means of the armature 7. Cup 15 is supported by a series of brackets 9, 10, 11, which are attached to the cup 15 and serve to support the switching mechanism upon the inner surface of the switchboard 25 in any convenient position. A shallow metallic cup 14 is secured to the magnetic cup 15 and is supported thereby, supporting in turn the metallic ring 13, which carries upon its outer surface the groups of springs 16, 17, 18, etc. The number of these groups of springs is limited only by the diameter of the ring 13 and the spacing of the groups thereon, the number employed depending upon the number of extensions to be served from a particular branch exchange. The armature 7 is carried upon the spindle 1, which further carries an arm 8 rigidly attached thereto. This arm 8 terminates in a knob 8' so positioned upon the arm 8 and so shaped as to register with and operate, on depression, the switches, as 16, 17, 18. A bushing 6, secured in an aperture provided therefor in the switchboard 25, admits and supports in a slidable manner the spindle 1. A hollow ratchet 4 is attached to the bushing 6 in a rigid manner and is provided with serrations corresponding with the number and spacing of the groups of switches employed. A flexible switch lever 2 is rigidly attached to the spindle 1 near its outer extremity and moves therewith. One end of the switch lever is bent to make contact simultaneously with the two conducting rings 20 and 21 when the spindle is

depressed. These rings are placed one within the other upon the face of the case 25, and are insulated from each other. The other end of the switch lever 2 is bent at substantially a right angle, and is provided with a tooth 2', which is formed to fit the serrations in the ratchet 4 and acts as a detent pawl. The spindle 1 is provided with a spring 5, which abuts at one end upon the bushing 6, and upon the other end upon a ring 1' rigidly attached to the spindle 1. This spring 5 is contained within the hollow portion of the ratchet member 4 and is adapted to maintain, through its compressive tension, the armature 7 normally out of contact with the poles of magnet 12. A knob 3 is securely fastened to the extended portion of the spindle 1 and serves as a means whereby the mechanism may be operated. It will be noted that as the groups of springs 16, 17, 18, etc., are radially spaced upon the ring 13, and as the ratchet is provided with serrations which coincide with the spacing of the groups of springs, that the arm 8, bearing the button 8', may be rotated to position the button 8' over any group of springs that may be selected. The switch lever 2 further acts as an indicator, and the positions of the groups of switch springs may be designated upon the outer surface of the case 25. Thus any particular group of springs may be selected by turning the knob 3 until the lever registers with the designating mark of the group desired. The button 8' is held over the group of springs in the position selected by means of the ratchet mechanism 4 and 5. The switches of a group are operated by means of the button 8', when the spindle 1 is depressed by means of the knob 3, to break one set of contacts and make another. It will be readily understood by those skilled in the art that, if the energization of the magnet 12 is accomplished by the operation just described, the spindle 1, carrying the arm 8, button 8' and lever 2, will be retained in its depressed position by means of the attraction of the magnet 12 for the armature 7 until such time as the energizing circuit is broken, whereupon the magnet 12 will be deenergized and allow the spindle, carrying the armature 7, to be returned to normal by means of the spring 5, and thereby restoring the apparatus to normal. The contact rings 20 and 21, together with that portion of the lever 2 bearing thereupon, constitute an electric switch, the use of which will be subsequently described.

It now remains to disclose the circuit arrangements in connection with the switching mechanism whereby the desired results are accomplished.

Referring to Fig. 4, in which I have illustrated an adaptation of my invention to use with a branch exchange operated on

the common battery principle, I have shown diagrammatically the electromagnetic multiple contact switch, previously described, at 16, 17, 18, 19, 12, 7 and 8, and the circuit connections necessary to adapt it to use with a branch exchange having four extension lines and one trunk to the central exchange. The balance of the circuit necessary to the operation of a branch exchange is also shown; however, this part will be only briefly explained, as the circuit arrangement is common and will be readily understood by those skilled in the art. Conductor 47 of the exchange line is connected to 15 an outer contact of each of the groups of switches 19, 18, 17 and 16. The conductor 48 of the exchange line, after passing through the non-inductive relay 50, is connected to the remaining outer contact of each of the groups of switches, 16, 17, 18 and 19. One contact of the relay 50 is connected through conductor 29 with one terminal of the magnet 12, the other terminal of which is connected to the local battery 25 9, which in turn is connected through its other terminal and conductor 30 to the remaining contact of relay 50. Four extension lines radiate from the branch exchange and are shown at 31, 32, 33 and 34. These 30 lines are connected to the movable springs of each of the switches 16, 17, 18 and 19, respectively. The movable springs of the extension line jacks 41, 42, 43 and 44 are connected to the inner contacts of the 35 switches 16, 17, 18 and 19, respectively. The exchange trunk line 47-48 is provided with a drop 52, which is bridged in series with a condenser 53 across the line. The trunk key 54 is connected directly across the trunk 40 line and is provided with a holding coil 55, which is connected to one set of contacts on the key. The operator's telephone set, shown at 56, is connected to the other set of contacts on the key 54 and is also connected to two contacts on key 27 of the operator's cord circuit 26. The drop 52 is conceived to be automatically restored when the key 54 is operated to place the operator in speaking connection with the exchange. 45 The drop signals associated with the answering jacks 41, 42, 43 and 44 are restored by the introduction therein of the plug of the operator's cord circuit 26. The mechanical restoration of line signals is well understood in the art, and it is not deemed necessary to enter more fully into the description. 50

The operation of the circuits and mechanism is as follows: When a calling signal is received from the central exchange the operator at the branch exchange operates key 54 to make contact between the movable and upper contacts, as viewed in Fig. 4, thereby connecting the operator's telephone set 56 with the trunk line and at the same

time automatically restoring the shutter of drop 52. After learning the extension line desired by the central exchange, the attendant inserts the calling plug of the cord circuit 26 in the jack associated with the extension line wanted and throws key 27 to the ringing position, thereby placing ringing current upon the extension line and ringing the bell at the extension subscriber's station. After receiving the response 75 from the subscriber rung, the operator moves the multi-contact switch to the group of switches, as 18, associated with the extension station just signaled and depresses the knob 3, thereby breaking contact between the movable contact springs and the inner contact springs on the switch 18, and making contact between the movable and outer contact springs on the same switch, thus connecting the conductors of the extension line, as 33, to the conductors 47 and 48 of the trunk line, and therefore placing the extension station in direct communication with the exchange. The subscriber upon the extension line, having answered 80 the signal, will therefore have his receiver removed from the hook, thereby completing a circuit for the passage of current from the common battery at the central exchange through the non-inductive relay 50, which 85 is actuated thereby to attract its armature and close the local circuit of the electromagnetic multiple contact switch through the coil 12 and local battery 9, thereby energizing magnet 12 and maintaining the 90 armature 7, carrying the arm 8 and the button 8', in a depressed condition, thus maintaining the exchange connection to the extension line. The non-inductive relay 50 is used in order that the talking efficiency 100 of the circuit may not be prejudicially affected. The key 54 is provided with a holding coil 55 in order that the operator, while signaling and receiving the answer 105 of the extension subscriber desired, may 110 hold the exchange trunk busy by throwing the key 54 to a position to place coil 55 across the trunk. At the termination of the conversation the subscriber replaces the receiver upon the hook, thereby opening the 115 circuit of the trunk line and giving the operator at the central exchange the disconnect signal, and also at the same time opening the circuit through relay 50, deenergizing the relay and thereby opening the local 120 circuit of the magnet 12, which results in deenergization of magnet 12, and thereby allowing armature 7, arm 8 and button 8' to be returned to normal by means of spring 5, Fig. 1. This restores switch 18 to normal and serves to disconnect extension 33 from exchange conductors 47 and 48. When a call is received from an extension line for an exchange line, the operator at the branch exchange calls the exchange by placing the 125 130

extension line upon the exchange trunk by means of the electromagnetic multiple contact switch, as described. This results in signaling the exchange operator, and the branch exchange operator or subscriber may request the called number from the exchange operator. Connections between extension lines are accomplished by means of the regular cords and plugs, as shown at 26, the battery for the operation of the subscriber's set on the extension line being shown at 28.

Referring to Fig. 5, in which I have illustrated an adaptation of my invention to use with branch exchanges of the magneto type, I have shown such a branch exchange, together with one trunk line and four extension lines. I have illustrated diagrammatically the electromagnetic multiple contact switch, previously described, at 16, 17, 18, 19, 12, 7 and 8. The exchange trunk line is represented by conductors 47 and 48, and the terminals of the four extension lines are represented at 31, 32, 33 and 34. Conductors 47 and 48 are multiplied to the outside contacts of switches 16, 17, 18 and 19. The extension lines 31, 32, 33 and 34 are connected to the movable springs of the switches 16, 17, 18 and 19, respectively, while the inner contacts of said switches are connected to the movable springs of the answering jacks 41, 42, 43 and 44 associated with the extension lines 31, 32, 33 and 34, respectively. The jacks are associated with drop signals which may be of any desired type and need no explanation, as their action is well understood in the art. The exchange trunk 47 and 48 is provided with a ring-down drop signal 52, which is normally bridged across the line through the normally closed contacts on the operator's or trunk key 55. The operator's telephone set 56 is bridged across the remaining contacts of key 55 and may be connected across the trunk thereby. A local battery 9 is connected to a terminal of the coil of the operating magnet 12 of the electromagnetic multiple contact switch, the remaining terminal of the coil 12 being connected to one contact of the switch 20 and 21, while the other contact of the switch is connected to one contact of the switch 54 through conductor 29, and the other contact of switch 54 is connected through conductor 30 to battery 9, thus placing the coil 12, switch 20, 21, and switch 54 in series in the circuit of the local battery 9. Switch 54 is arranged to open the local battery circuit through the magnet coil when ring-down drop 52 is energized to release its shutter. The ring-down drop 52, which is of the ring-down type usual in magneto type systems and requires generator current for its operation, is conceived to be restored whenever the key 55 is operated to connect the operator's telephone set to the exchange trunk line, this restoration

being accomplished in any one of a number of ways well known in the art. Switch 20 and 21 is a diagrammatic representation of the rings 20 and 21 and a portion of the lever 2 of Fig. 1, and is adapted to operate to close whenever the knob 3 of the electromagnetic switch is depressed.

The operation of my invention, when adapted to use with branch exchanges of the magneto type, is as follows: When the call is received from the exchange the operator at the branch exchange moves key 55 to a talking position, thereby bridging the operator's telephone set 56 across the trunk and disconnecting the drop 52 from the line. This movement of key 55 also, by mechanical means, restores drop 52 to normal and allows switch 54 to close. After learning the requirements of the exchange the branch exchange attendant places the calling plug of the cord circuit 26 in the jack, as 43, associated with the extension line desired and moves key 27 to a ringing position, thereby placing ringing current upon the extension line and ringing the bell at the extension subscriber's station. After receiving a response from the subscriber rung, the operator moves the indicator of the electromagnetic multiple contact switch to the group of switches, as 18, associated with the extension just signaled, and depresses the knob 3, thereby breaking contact between the movable contact springs and the inner contact springs on the switch 18 and making contact between the movable and outer contact springs on the same switch, thus placing the conductors of the extension line, as 33, in connection with the trunk line conductors 47 and 48, and therefore placing the extension in direct communication with the exchange. Upon the depression of the knob 3 of the electromagnetic multiple contact switch in the operation of connecting the extension line to the exchange trunk line, switch 20 and 21 will be closed, and, as switch 54 has previously been closed by the restoration of drop 52 to normal by the operation of the key 55, there will be completed a local circuit as follows: key 54, conductor 30, battery 9, coil of magnet 12, switch 20-21 and conductor 29. Magnet 12 will therefore be energized to attract its armature 7 and will thus retain the electromagnetic multiple controlled switch in a depressed condition until the local circuit is broken. The connection between the extension line called and the exchange is therefore maintained electromagnetically during conversation. At the termination of the conversation, the subscriber at the extension instrument replaces the receiver upon the hook and rings back on the line with the generator, as is usual in the operation of magneto systems. The ring down drop 52, being bridged across the line, is operated by

the generator current received from the extension station and releases the shutter 53. The shutter, when released, opens switch 54 and hence opens the local circuit through 6 the electromagnet 12, deenergizing this magnet and causing the armature 7, carrying arm 8, button 8' and lever 2, to be restored to normal through the tension of spring 5, Fig. 1, thus disconnecting the extension line 10 from the exchange line and connecting the extension line to its associated jack; thereby restoring the apparatus at the branch exchange to normal. When a call is received from an extension line for an exchange 15 line, the operator at the branch exchange notes the number of the extension signalling and moves the indicator of the electromagnetic multiple contact switch to the group of springs associated with the calling extension. The operator then depresses the 20 electromagnetic switch, having previously operated switch 55, to remove the ring down drop 52 from the extension line and place the operator's telephone set 56 across the exchange trunk line. The operator then requests the subscriber at the extension instrument to ring again, thus signaling the central exchange, the connection being maintained during conversation, and being automatically disconnected on the cessation of 25 conversation, as previously described. Local calls, or calls between extension lines connected to the same branch exchange, are handled in the usual way by means of the 30 jacks 41, 42, 43 and 44 and the connecting cord circuit 26.

It will be noted in the application of my invention disclosed in Fig. 4 that the necessity for a holding coil associated with switch 35 54 could be eliminated in systems in which ringing current is supplied from the central exchange, by providing a ringing key for each extension line, in which case the attendant at the branch exchange, upon receiving a call for an extension, would depress the key associated with the line called and ring until the line indicator denoted a reply, and then move the multiple contact switch to the group of springs associated 45 with the line calling, thus obviating the necessity for a holding coil being placed across the exchange trunk while the operator is calling an extension.

It is obvious that, when my device is utilized in connection with common battery systems in which the exchange trunk is of comparatively short length and consequently of low resistance, the use of the non-inductive relay 50 is not necessary and 50 I may eliminate the use of local battery 9 and cause the energization of magnet 12 by means of current from the central station battery supplied over the exchange trunk 47 and 48, as illustrated in Fig. 6, in 55 which I have shown in diagram the magnet

12 connected directly across the exchange trunk 47 and 48 and shunted by a non-inductive resistance 51, thus eliminating the use of the non-inductive relay 50 and the battery 9 of Fig. 4.

The advantages of the facilities afforded by my invention are obvious, as it is only necessary on the part of the branch exchange attendant to establish the connection, when all responsibility on the part of the attendant at once ceases, thus eliminating to a large extent the personal equation of the attendant, and thereby tending to greatly increase the speed of telephone service and the efficiency of operating. Further, in the case of night calls through a branch exchange, the night or alarm bell is used in connection with the line indicators, thus providing an audible signal. But frequently the night bell is not connected with the supervisory signals, so that no audible signal is given upon the cessation of conversation; therefore a connection between an extension line and the central exchange is frequently retained long after conversation has been completed and tends to the detriment of the service.

It is obvious from the foregoing that branch exchanges having more than one trunk line may be equipped with an electromagnetic multiple contact switch for each trunk line, the extension line and jack connections being multiplied through each switch, thus enabling the operator at the branch exchange to connect any extension to any trunk and vice versa.

While I have illustrated and described certain embodiments of my invention, it is understood that numerous changes may be made therein without departing from the spirit or narrowing the scope of my invention.

Having thus described my invention, what I claim as new and desire to secure by United States Letters Patent is:

1. In a telephone switching system, an exchange; a branch exchange; a trunk line extending therebetween; a plurality of extension lines radiating from said branch exchange; a plurality of line jacks, one associated with each of said extension lines; a switching mechanism at said branch exchange and associated with said trunk line, said extension lines being normally in contact with their respective line jacks through said switching mechanism, said switching mechanism being adapted to selectively remove one of said extension lines from connection with its respective line jack and place said extension line in connection with said trunk line; electromagnetic means associated with said switching mechanism whereby said extension line is maintained in connection with said trunk line during traffic over such connection, and whereby said

- 6
- extension line may be automatically released from connection with said trunk line and restored to connection with its respective line jack at the termination of said traffic.
5. 2. In a telephone switching system, an exchange; a branch exchange; a trunk line extending therebetween; a plurality of extension lines radiating from said branch exchange; a line jack associated with each of 10 said extension lines; an electromagnetic switch mechanism at said branch exchange and associated with said trunk line; said line jacks being normally connected with their respective extension lines through said 15 switch mechanism, said switch mechanism being adapted to selectively remove one of said extension lines from connection with its respective line jack and place said extension line in connection with said trunk line; said 20 electromagnetic switch mechanism being further adapted to maintain said extension line in connection with said trunk line during traffic over such connection and to automatically disconnect said extension line 25 from said trunk line, and restore said extension line to connection with its respective line jack at the instant of termination of said traffic.
3. In a telephone switching system, an exchange; a branch exchange; a plurality of trunk lines extending therebetween; a plurality of extension lines radiating from said branch exchange; a plurality of switching mechanisms at said branch exchange, 30 one associated with each of said trunk lines; a plurality of line jacks, one associated with each of said extension lines, said line jacks being normally connected through each of said switching mechanisms in multiple with their respective extension lines, each of said switching mechanisms being adapted to selectively remove one of said extension lines from connection with its respective line jack and place said 35 extension line in connection with said trunk line; electromagnetic means associated with each of said switching mechanisms whereby said extension line is maintained in connection with said trunk line during traffic over 40 such connection, and whereby said extension line may be automatically released from connection with said trunk line and restored 45
- to connection with its respective line jack at the termination of said traffic.
4. In a telephone switching system, a plurality of exchanges; a branch exchange, 55 trunk lines extending between said exchanges and said branch exchange; a plurality of extension lines radiating from said branch exchange; a plurality of electromagnetic switch mechanisms at said branch exchange, each of said switch mechanisms being associated with one of said trunk lines respectively; a line jack associated with one of each of said extension lines, said line jacks 60 being normally connected through each of said switch mechanisms in multiple with their respective extension lines; said electromagnetic switch mechanism being adapted to selectively remove any one of said extension lines from connection with its associated line jack and place said extension line 65 selectively in connection with any one of said trunk lines; said electromagnetic switch mechanism being further adapted to maintain said extension line in connection with said trunk line during traffic over such connection, and further to automatically release said extension line from said trunk line and restore said extension line to connection 70 with its respective line jack at the termination of said traffic.
5. In a telephone system, a switching device consisting of a shaft capable of rotary and longitudinal movements; a contact actuating member carried by said shaft and partaking of its movements; a group of spring contacts lying adjacent to the circular path of said contact actuating member; means for manually rotating said shaft to select 75 one of said group; means for moving said shaft longitudinally to cause said contact actuating member to engage the springs of said group; an electromagnet adapted to hold said shaft in its engaging position, and 80 means controlled over a connected telephone line for deenergizing said magnet to release said shaft, substantially as described.
- Signed by me at Liverpool, in England, in the presence of two witnesses.
